UNITED STATES PATENT OFFICE.

WILLIAM M. WHEILDON, OF BOSTON, MASSACHUSETTS, ASSIGNOR TO ARTHUR MURPHY,
SR., OF QUINCY, MASSACHUSETTS.

LOOSE-LEAF BINDER.

No. 902,189.

Specification of Letters Patent.

Patented Oct. 27, 1908.

Application filed August 9, 1906. Serial No. 329,830.

To all whom it may concern:

Be it known that I, WILLIAM M. WHEILDON, a citizen of the United States, and resident of Boston, in the county of Suffolk and State of Massachusetts, have invented new and useful Improvements in Loose-Leaf Binders, of which the following is a specification.

My invention relates to the construction of loose leaf binders for loose leaf ledgers, memorandum books and the like and it consists in sundry improvements herein described.

In the drawings hereto annexed, Figure 1 is a perspective view of my new loose leaf binder in its closed or leaf retaining position. Fig. 2 is a similar view of my loose leaf binder in its open or leaf-receiving position. Fig. 3 shows a modification. Fig. 4 shows another modification. Fig. 5 shows a retaining means which may be used to hold my loose leaf binder in its closed position.

The preferred form of binder is illustrated in Figs. 1 and 2 and the preferred retaining means is shown in Fig. 5. In the preferred form the device consists of two flat bars, A and A', usually made of metal, pivoted together at B near their middle portions, each bar carrying an upwardly extending leaf receiving member a on opposite ends and opposite sides. The loose leaves are suitably perforated or punched to receive the ends of the leaf receiving members, preferably a member on one end of the bar and a member on the opposite end of the other bar. The punched or slotted leaves are adjusted over these members while the device is in the open position shown in Fig. 2, and the device is then closed, the respective opposed leaf receiving members a upon the bars coming together to form a complete ring or loose leaf retaining member from which the leaves cannot escape. When so closed and the leaves thus threaded upon the two rings thus formed, the device is inserted in the channel C of metal or other suitable material shown in Fig. 5, and the two bars thus locked in their operative leaf-retaining position. The channel C shown in Fig. 5 is designed to be secured by suitable rivets or otherwise to the cover of the account book or memorandum book.

Any desired number of leaves or sheets within the capacity of the leaf-retaining rings may be threaded in the manner described, and any sheet may be withdrawn or inserted at will without disturbing the ar-

rangement of the other sheets upon the binder. In the device shown in Fig. 3 the half rings a' of the leaf receiving members which, as shown in Fig. 1, are upon opposite sides and opposite ends of each plate, are differently arranged and the pivot point B' is also at one end of the two bars, instead of central of the two bars as shown in Figs. 1 and 2. The mode of operation is similar to the mode of operation of the device shown in Figs. 1 and 2.

In the modification shown in Fig. 4 the two bars A, A' are substantially identical in organization and structure with the bars shown in Figs. 1 and 2, and they are pivoted at their middle portions at B' as is the device of Figs. 1 and 2, but a retaining means different from that employed in Figs. 1 and 2 is shown, viz. a spring finger D upon the end of one bar and a corresponding recess E in the end of the other bar, organized and arranged to interlock when the two bars are brought into their closed or leaf-retaining position.

It is obvious that the locking means to hold the parts of my loose leaf binder in operative or closed position may be either the means shown in Fig. 4 or the means shown in Fig. 5, and many other suitable locking means to hold the two parts together in closed position may be used.

I further design to utilize the central pivot shown in Fig. 4 to connect the binder with the cover of the book in which it is employed.

I claim:

1. A loose-leaf binder, consisting of two bars each having a leaf-receiving half member secured thereto in opposed and coöperating relation to a half member upon the other bar, the said bars being movably secured together by a pivot pin; means to retain the two bars in their leaf retaining position, all organized and arranged substantially as shown and described.

2. A loose-leaf binder, consisting of two bars each having a leaf-holding half member secured thereto upon opposite sides and ends, the said bars being pivotally connected at their middle portions, and a channel, properly shaped and proportioned to receive the two bars in their leaf retaining position, all organized and arranged substantially as shown and described.

3. A device of the character described comprising two members each supplied with a plurality of leaf holders, pivoted together by a pivot parallel to the plane of said leaf

holders at a point lying between the outermost leaf holders supported by each member and adapted to permit one of said members to rotate about said pivot through a limited 5 arc, and means for locking said members together when closed.

4. A device of the character described, comprising two members, each provided with a plurality of leaf holders and pivoted together by a pivot parallel to the plane of said leaf holders at a point intermediate the outermost leaf holders, a protuberance on one of said members, and an opening in the other member adapted to coöperate with said protuberance to lock the members together when 10 in closed position.

5. A device of the character described, comprising two superimposed members pivoted together by a pivot extending transversely through both members and each 15 provided with a plurality of curved members adapted to coact in pairs to form suitable

leaf holders; and means for locking said members together.

6. A device of the character described 25 comprising two flat members pivoted together by a pivot at right angles to said flattened sides at a point substantially midway of the length of one thereof and adapted to be moved relative to each other about the 30 axis of said pivot, a leaf holder on each member located at each side of said pivot and extending therefrom in a plane parallel with said pivot and coöperating with the oppositely opposed leaf holder on the other member, and means for locking the members together when said leaf holders are in coöperating 35 position.

Signed by me at Boston, Massachusetts, this 23rd day of July, 1906.

WILLIAM M. WHEILDON.
